DESIGN FOR A JAR OR SIMILAR ARTICLE.

Application filed April 14, 1925. Serial No. 13,127. Term of patent 14 years.

To all whom it may concern:

Be it known that I, LOUIS P. PIAZZOLI, Jr., a citizen of the United States, residing at Connellsville, county of Fayette, State of Pennsylvania, have invented a new, original, and ornamental Design for Jars or Similar Articles, of which the following is a specification, reference being had to the accompanying drawings, forming a part thereof.

Figure 1 is a top plan view of a fancy jar, showing my new design;

Figure 2 is a front elevational view of the same, and

Figure 3 is an elevational view of a jar positioned to show two sides thereof.

Dominant features of the invention are a plurality of vertical ribs projecting from the side wall of the jar, and the shape of the side walls which forms elongated curves when the jar is viewed in elevation, and substantially sectors of circles, in plan view.

I claim:

The ornamental design for a jar or similar article substantially as shown and described.
